UNITED STATES PATENT OFFICE.

ANDRÉ M. MERTZANOFF, OF BUFFALO, NEW YORK, ASSIGNOR TO AMERICAN RADIATOR COMPANY, OF CHICAGO, ILLINOIS, A CORPORATION OF NEW JERSEY.

DESIGN FOR A BOILER.

53,663.

Specification for Design.

Patented July 29, 1919.

Application filed August 7, 1918. Serial No. 248,813. Term of patent 14 years.

To all whom it may concern:

Be it known that I, ANDRÉ M. MERTZANOFF, a subject of the King of Greece, residing at Buffalo, Erie county, in the State of New York, have invented a new, original, and ornamental Design for a Boiler, of which the following is a specification, reference being had to the accompanying drawing forming part thereof.

In said drawing;

Figure 1 is a front view showing a boiler embodying or incorporating my said design;

Fig. 2 is a side view thereof;
Fig. 3 is a back view thereof, and
Fig. 4 is a top view.

I claim:

The ornamental design for a boiler as shown.

ANDRÉ M. MERTZANOFF.

Witnesses:

CONRAD A. DIETERICH,
F. C. HALSEY.
